UNITED STATES PATENT OFFICE.

BEN ALFRED BALL, OF PAWTUCKET, RHODE ISLAND, ASSIGNOR TO AMERICAN TEXTILE CO., INC., OF PAWTUCKET, RHODE ISLAND, A CORPORATION OF RHODE ISLAND.

DESIGN FOR LACE.

Application filed July 22, 1927. Serial No. 22,850. Term of patent 3½ years.

To all whom it may concern:

Be it known that I, BEN A. BALL, a citizen of the United States and a resident of Pawtucket, in the county of Providence and State of Rhode Island, United States of America, have invented a new, original, and ornamental Design for Lace, of which the following is a specification, reference being had to the accompanying drawing, forming part thereof.

The figure is an elevation of the lace embodying my new design.

I claim:

The ornamental design for lace, as shown.

BEN ALFRED BALL.
